SUCTION NOZZLE

Eric Edström, Stockholm, Sweden, assignor to
Electrolux Corporation, Dover, Del., a corpora-
tion of Delaware

Application June 26, 1936, Serial No. 87,398
In Switzerland July 2, 1935

3 Claims. (Cl. 15—155)

My invention relates to suction nozzles for use in connection with a vacuum cleaner and particularly to a nozzle provided with a large opening and having a valve member which may be selectively positioned so as to obtain a substantially uniform flow of air through the entire length of the nozzle opening, or so as to obtain a concentrated flow restricted substantially to a small portion of the nozzle opening. When the entire opening is in use it will cover a larger surface, thereby increasing the speed of cleaning. However, if a concentrated suction is desired in order to remove dirt which air flowing through the entire opening will not pick up, a more concentrated flow through the restricted portion may be obtained.

The objects and advantages of my invention will be apparent from the following description considered in connection with the accompanying drawing which forms part of this specification, and of which:

Fig. 1 is a cross-sectional view of a preferred embodiment of my invention;

Fig. 2 is a cross-sectional view taken on the line 2—2 of Fig. 1;

Fig. 3 is a cross-sectional view taken on the line 3—3 of Figs. 1 and 2; and

Fig. 4 is a view similar to Fig. 3 but showing the parts in a different position.

Referring to the drawing, reference character 10 designates generally a nozzle including a cylindrical portion 11 adapted to be connected to a source of suction and an elongated hollow portion 12 formed with an elongated suction opening 13. Cylindrical portion 11 communicates with elongated portion 12 through an opening 14. A valve member 15 is rotatably mounted by means of a screw 16 within an elongated portion 12. The valve member includes cylindrical portions 17 and 18 between which are formed ports 19 and 20 and may be turned by a handle 21 extending through a slot 22.

With the parts in the position shown in Figs. 1 through 3 it will be seen that port 19 communicates with both the opening 14 to the cylindrical portion 11 and one side of the elongated portion 12, while the port 20 communicates with the other side of the elongated portion. Consequently, air will be drawn into the hollow portion 11 from all parts of the elongated portion.

If it is desired to obtain a concentrated flow of air at one point, the valve member 15 is turned to the position shown in Fig. 4, where the port 19 communicates only with the opening 14 and the port 20 is closed by the wall of the nozzle. In this position all of the air drawn in must

flow through the open lower end of the valve member, whereby a concentrated flow of air is obtained, which is able to pick up objects which resist the more widely distributed flow through the elongated opening 13.

While I have shown and described one more or less specific embodiment of my invention it is to be understood that this has been done for purpose of illustration only, and that the scope of the invention is not to be limited thereby, but is to be determined by the appended claims viewed in the light of the prior art.

What I claim is:

1. A suction nozzle including a hollow body portion having fixed structure forming an elongated undivided and continuous suction opening and an outlet adapted to be connected to a source of suction, and a hollow cylindrical member having an open bottom and ported sides rotatably mounted in said body portion, said member being rotatable between a position in which said ports establish communication between said outlet and all portions of said elongated opening and a position in which said sides restrict the area of said opening which is in communication with said outlet to that defined by the open bottom of said member.
2. A suction nozzle including a hollow body portion having fixed structure forming an elongated undivided and continuous suction opening, and a cylindrical rotatable valve member having its axis disposed substantially at right angles to the lengthwise extent of said elongated opening and provided with a port permanently in communication with a portion of said opening which is restricted and defined by said valve member when the latter is in one position and with a port which communicates with an additional portion of said opening when the valve member is rotated to another position.

3. A suction nozzle including a hollow body having fixed structure forming an elongated undivided and continuous suction opening, and a cylindrical rotatable valve member located centrally with respect to the lengthwise extent of said elongated opening and having its axis disposed substantially at right angles to said lengthwise extent, said valve member being provided with a port permanently in communication with a central portion of said opening which is restricted and defined by said valve member when the latter is in one position and with ports which communicate with the end portions of said opening when the valve member is rotated to another position.
